UNITED STATES PATENT OFFICE.

EDWARD R. CONKLIN, OF WAUSEON, OHIO, ASSIGNOR TO THE CONKLIN AUTOMATIC CULTIVATOR COMPANY.

CULTIVATOR.

SPECIFICATION forming part of Letters Patent No. 443,703, dated December 30, 1890.

Application filed February 8, 1890. Serial No. 339,761. (No model.)

To all whom it may concern:

Be it known that I, EDWARD R. CONKLIN, a citizen of the United States, residing at Wauseon, Fulton county, Ohio, have invented certain new and useful Improvements in Cultivators, of which the following is a specification.

My invention relates to that class of wheel-cultivators in which the driver's weight balances and takes from the neck of the horses the weight of the pole and the downward drag of the shovel-beams or drag-bars. In this class of cultivators, when the suspended plows or teeth are in the ground, the weight and downward pull of the pole on the necks of the horses are greater than when the plows are out of the ground.

The object of my invention is to provide a simple, cheap, and efficient means for shifting the axle of my cultivator to and fro by the same movement by which the cultivator-teeth are raised or lowered, thus shifting the fulcrum so that the weight and downward pull of the pole upon the necks of the horses may be kept substantially uniform, regardless of whether the plows are raised or lowered. I attain this object by means of the mechanism hereinafter described, and shown in the accompanying drawings, made part hereof, in which—

Figure 1 is a side elevation of my cultivator; Fig. 2, a plan view; Fig. 3, a side view of the same with one of the wheels and one of the drag-bars removed; Figs. 4 and 5, side elevation of fulcrum-shifting lever in different positions, and Fig. 6 a plan of said lever and its attachments in detail.

Like letters represent like parts in the several views.

40 A is the main frame of the machine. This frame I prefer to form of gas-pipe and gas-pipe connections, as illustrated in Fig. 2.

B is a bar or pipe extending across and rigidly fixed to the frame, giving rigidity thereto and serving as an axle for the rotating parts hereinafter referred to.

C are the wheels of the machine. To the forward end of the frame is attached in the usual manner the tongue D of the machine.

45 At the opposite and rear end of the frame the seat for the driver (not shown in the draw-

ings) is suspended in the usual manner from midway between the extremities of the pieces composing the frame, the driver's feet resting in stirrups s.

55 The axle for the wheels does not extend across the width of the machine; but the wheels revolve on spindles c, Fig. 3, rigidly fixed to and projecting outwardly from the lower part of U-shaped standards E, the arms 60 of which extend upwardly, terminating in loops or openings e. These loops or openings loosely embrace the side pieces forming frame A, so that, the frame being stationary, the loops slip to and fro lengthwise of the frame, 65 carrying with them the standards and wheels of the machine, or so that, the wheels being stationary, the frame slips to and fro longitudinally in the loops, or so that both the frame and loops may move to and fro reciprocally.

Now, assuming that the driver is in his place in the seat suspended between the rear extremities of the frame A and that his weight exactly balances the weight of the tongue, it 75 is clear that if the frame be moved forward in its bearings in loops e, the fulcrum being shifted nearer the driver, the tongue will press downward, while if the frame be moved in its bearings in the opposite direction the fulcrum will be shifted away from the driver 80 and the tongue will press upward. Thus it will be seen that by sliding the loops e to and fro upon the frame A the weight of the pole or tongue upon the horses may be adjusted 85 as desired.

My machine is provided with two drag-bars F F, attached and pivoted by their forward ends to the bottom of the main frame near its front end. These drag-bars are provided with the usual shovels, plows, or teeth, and may be raised and lowered independently of each other by means of chains G, connecting the drag-bars with levers H, fulcrumed and pivoted at their lower extremities on 90 cross-bar B. Levers H are provided with pawls h, which may be made to engage curved racks i on cross-piece B, retaining the levers at any desired point in their throw, thus sustaining the drag-bars at any desired height. 95 Racks i are fixed upon sleeves k, which rotate on cross-bar B. The sleeves are each 100

provided at their outer ends with a downwardly-projecting arm *l*, attached rigidly thereto. Arms *l* are slotted longitudinally, the slots receiving pins *m*, projecting from 5 the inner face of standards *E*.

When standards *E*, with their loops *e*, are slipped to and fro on frame *A*, projecting pins *m* on standards *E* slide in slotted arms *l*, causing the same to describe the arc of a circle of which cross-bar *B* is the center. This 10 motion of arms *l* rotates sleeves *k*, and with them racks *i*, which, being engaged with levers *H* by means of pawls *h*, cause the throw 15 of levers *H*, which, through chains *G*, raise and lower the drag-bars *F*.

N is a lever, the upward end of which has a handle within convenient reach of the operator. This lever is fulcrumed near its lower end to link or bar *o*, which extends forward to 20 and is pivoted on a block near the front end of the frame *A*. The lower end of lever *N* is pivoted to a collar fixed on rod *p*, which is adapted to slide longitudinally in suitable supports provided near its two ends. Attached to 25 and leading forward from standards *E* are two stout rods *q*, which converge and are fastened to rod *p*.

Assuming that the plows are lowered to the ground, the position of the other parts will be 30 as follows: Levers *H* will be thrown backward toward the driver, with their pawls *h* engaging the racks *i*, the handle of lever *N* will be thrown back toward the driver, rod *p* will be pushed forward, and standards *E*, 35 with the wheels, will be slipped to their forward limit. Arms *l* will also be thrown to their forward limit, while sleeves *k* and racks *i* are turned on their axis to their backward limit. In this position either of the drag-bars, 40 with its attached shovels, may be raised and lowered independently by means of its lever *H*, so as to avoid obstructions and straggling plants; but if it is desired to raise both drag-bars at once the operator throws forward the 45 handle of lever *N*, which throws backward the lower end of the lever, carrying with it rod *p* and its attached rods *q*, which slide standards *E* backward on frame *A*, shifting the fulcrum of the machine backward. This 50 backward movement of the standards *E* by means of pins *m* moving in the slots of arms *l* causes arms *l* to swing backwardly, rotating sleeves *k* and racks *i* forward, carrying with them levers *H*, which, through chains *G*, 55 lift both drag-bars simultaneously.

The position of lever *N* and its attachments when the plows are lowered and when the weight of the driver is farthest from the fulcrum is shown in Fig. 4. The opposite position of the lever *N*, with the opposite result, is shown in Figs. 5 and 6. Thus it will be seen that the equilibrium of the machine is maintained and the weight of the pole or

tongue is kept balanced by the weight of the driver by the same operation which throws 65 the plows into or out of the ground.

What I claim as my invention, and desire to secure by Letters Patent, is—

1. In a cultivator, the drag-bar raising and lowering mechanism, in combination with the 70 frame-supporting mechanism movable longitudinally upon said frame, said drag-bar raising and lowering mechanism adapted to be actuated by the horizontal movement of the frame-supporting mechanism, substantially as shown and described, for the purpose specified.

2. In a cultivator, the frame-supporting mechanism adapted to move horizontally along the frame of such machine, in combination with the mechanism for raising and lowering the drag-bar, whereby the drag-bars may be raised or lowered and the fulcrum of the machine may be shifted by the same 80 operation, substantially as shown and described, for the purpose specified.

3. In a cultivator, standards *E*, provided with wheel-spindles and adapted to support and move horizontally to and fro along the frame of the machine, in combination with 90 lever *N*, fulcrumed to the frame of the machine, and the mechanism intermediate said lever and said standards, substantially as shown and described, for the purpose specified.

4. In a cultivator, levers *H*, adapted to raise and lower the drag-bars of the machine, in combination with the supporting mechanism of the frame *A*, adapted to move to and fro along said frame, and the mechanism intermediate said levers and said supporting mechanism, substantially as shown and described, for the purpose specified.

5. In a cultivator, lever *N*, adapted to move the frame-supporting mechanism to and fro 105 horizontally along said frame, in combination with levers *H*, adapted to raise and lower the drag-bars of said machine, and the mechanism intermediate said levers *H* and *N*, substantially as shown and described, for the 110 purpose specified.

6. In a cultivator, the combination of lever *N*, link or bar *o*, rod *p*, and rods *q* with standards *E*, substantially as shown and described, for the purpose specified.

7. In a cultivator, lever *N*, link or bar *o*, rod *p*, rods *q*, and standards *E*, in combination with pin *m*, slotted arm *l*, sleeve *k*, rack *i*, pawls *h*, levers *H*, chains *G*, and drag-bars *F*, substantially as shown and described, for 120 the purpose specified.

E. R. CONKLIN.
